US00D609063S

(12) **United States Design Patent**
Pang

(10) **Patent No.:** **US D609,063 S**
(45) **Date of Patent:** **** Feb. 2, 2010**

(54) **CUTTING BOARD**

(75) Inventor: **Chi Kong Pang**, Hong Kong (HK)

(73) Assignee: **SAR Holdings International Limited**,
Hong Kong (HK)

(**) Term: **14 Years**

(21) Appl. No.: **29/341,738**

(22) Filed: **Aug. 12, 2009**

(51) **LOC (9) Cl.** **07-04**

(52) **U.S. Cl.** **D7/698**

(58) **Field of Classification Search** **D7/388, D7/409, 505, 549, 552.2, 553.5, 553.8, 554.2, D7/555, 566, 587, 624.1, 637-638, 667, 673, D7/696, 698-699; D9/440, 447, 454; D10/46.3; D27/126; 99/446, 449; 220/23.6; 269/13-16, 269/54.5, 289 R, 291-292, 297-298, 302.1**

See application file for complete search history.
